UNITED STATES PATENT OFFICE.

SAMUEL A. E. HICKSON, OF FULFORD, ENGLAND.

ROTARY PRESSURE-ENGINE.

SPECIFICATION forming part of Letters Patent No. 642,225, dated January 30, 1900.

Application filed October 9, 1899. Serial No. 733,097. (No model.)

To all whom it may concern:

Be it known that I, SAMUEL ARTHUR EINEM HICKSON, a subject of the Queen of England, residing at Ash Villa, Fulford, in the county 5 of York, England, have invented a certain new and useful Improved Rotary Pressure-Engine, (for which I have made application for Letters Patent in Great Britain, No. 25,092, dated November 28, 1898, and No. 19,341, dated September 26, 1899,) of which the following is a specification.

This invention relates to an improved rotary engine or motor which may be driven by fluid-pressure, such as steam.

15 In carrying out this invention the cylinder of the engine comprises an annular chamber which may be formed within a casting, one side of the casting being open. This open side of the casting is closed by a disk, herein- 20 after called the "crank-disk," carried fast upon the engine-shaft, which passes through the casting within which the annular chamber is formed and is arranged concentric with the said chamber. The disk is provided with a 25 crank-pin or piston, which is made to accurately fit the chamber or cylinder, so that it may travel freely in the same, carrying with it the crank-disk, to which it is attached. The crank-pin or piston is propelled by admitting 30 steam, for instance, on one side of it, while all pressure is removed from the opposite side. To effect this, one or more reciprocating partitions are provided and arranged in such a manner that as they reciprocate they divide 35 the cylinder behind the piston. Steam is admitted between any one such partition when in position across the cylinder and the piston, so that the piston is propelled forward in the chamber, an exhaust being opened on that 40 side of the partition toward which the piston is traveling. As the piston nears the partition, which now projects across its path, the partition is withdrawn and is again replaced after the piston has passed that point.

45 To avoid a dead-center, two reciprocating partitions are preferably used, which alternately project across and are withdrawn from the annular chamber or cylinder; also, to obviate end thrust on the crank-disk and its 50 shaft two chambers may be arranged one on either side of the disk. The disk is in this case provided with two pistons, the other parts

of the machine being duplicated. Slide-valves may be used to regulate the admission of steam to the annular chamber or cylinder and also to exhaust, or the partitions may themselves be used as slide-valves for this purpose, and they may be reciprocated either mechanically or by steam or other pressure.

In the accompanying drawings, which illustrate one method of carrying out this invention, more particularly in view of the engine being driven by steam, Figure 1 is a side elevation of the engine. Fig. 2 is a horizontal section of Fig. 1 on the line 2 2. Fig. 3 is a 65 vertical section of Fig. 2 on the line 3 3; and Fig. 4 is a transverse central section of Fig. 3, viewed as indicated by an arrow.

Like letters indicate like parts throughout the drawings.

70 The engine framing or casing comprises two castings A, having each an annular chamber B. The chamber B in each case is accurately bored, a core A', which is part of the casting A, being left in its center. The castings A 75 are each provided with lugs A², with which they may be bolted together, so that the two chambers B form one common chamber, which, however, is divided again into two separate chambers by a crank-disk C, carried by its 80 shaft C'. The shaft C' passes through both of the castings A, being carried in suitable bearings in the same, and projects beyond the outside of each. The crank-disk C carries on either side of it a crank-pin or piston C², 85 which is made to exactly fit the chamber B. In each chamber in a horizontal plane passing through the axis of the shaft C' are arranged two reciprocating partitions D, one on either side of the shaft, which when in their 90 forward position project across the chamber B and enter recesses D' in the core A' of the casting A. These partitions D are made to exactly fit the chamber B, so that when one partition is closed the chamber is divided 95 into two steam-tight compartments, each limited by the partition and the piston or crank-pin C², respectively. The partitions are each provided with an extension D'*; those on one side of the shaft being connected together by 100 a cross-head D² and those on the other side being similarly connected by a cross-head D³. The cross-heads are carried in guides D⁴, which may be of any convenient construction

and secured in any well-known manner to the castings A; also, the partitions D have tenons on their outer edges, which run in grooves in the faces of the castings A and serve to 5 guide the partitions in their reciprocations across the chamber B. The ends of the cross-heads D² D³ are provided with journals D⁵, whereby they are connected by connecting-rods D⁶ to double eccentrics D⁷ on the engine-shaft C'. By this means as the shaft C' revolves the partitions on one side of the shaft are made to advance, while those on the other simultaneously retire.

Within each casting are formed ports, each 15 of which communicates with one of the chambers B, the ports E being arranged to admit live steam to the cylinder or chamber B, while the ports E' are connected with the exhaust. The faces of the partitions D are recessed at D⁸, so 20 that when either partition is in the forward position the ports E E' are in free communication with the chamber B, the steam and exhaust ports being thus both open, while both are again immediately closed as the partition is 25 withdrawn. Within the core A' a balance-chamber A³ is formed around the shaft C' and communicates with the recesses D', so that the same pressure is maintained upon the ends of the partitions on the right as upon 30 those on the left of the shaft. To prevent steam from the balance-chamber A³ escaping between the shaft C and its bearings in the castings A, stuffing-boxes and glands of any well-known construction may be provided, 35 though none are shown in the drawings.

To regulate the admission of steam to the ports E and to control the exhaust E', they may be brought together at the top and bottom of the engine and inclosed by a steam-box F. The steam-box F communicates with a steam-pipe F', and within it is arranged in the usual well-known manner a slide-valve F². In the particular construction shown in the drawings the slide-valves F² are not regularly reciprocated, but are controlled by any 45 convenient mechanism, such as a worm and worm-wheel device G, whereby they may be either made to open or close the admission-ports relatively to the exhaust-ports, or in 50 case of it being required to reverse the direction of the engine the ports E may be converted into exhaust-ports, while those marked E' may be made the admission-ports.

The operation of the engine is as follows:

55 Steam being admitted by the port E, as indicated by the arrow in Fig. 3, it is unable to escape from between the partition on the right of the shaft and the crank-pin or piston C², both of which are made to be steam-tight 60 fittings within the chamber B, so that the partition being immovable the piston C² is propelled forward, expelling any steam which is in the front of it by the exhaust E'. On, however, approaching the partition which projects across its path the eccentric D⁷ on the shaft C' withdraws the said partition by means of its cross-head D² and connecting-

rod D⁶ and at the same time advances the partition on the left across the chamber B and into the core A' by means of its cross-head D³. The ports on the right of the engine are thus closed, while those on the left are open. By this means steam is again admitted behind the piston, while an exhaust is 75 opened on that side toward which the piston is traveling. Therefore the piston continues its motion in the same direction as before. As the partitions on one side of the shaft are connected to the cross-head D² and those on the other side to the cross-head D³, it is obvious 80 that the operations in each chamber B will take place at the same time, so that an equal pressure will be maintained upon either side of the crank-disk C.

It is found in practice that for the engine 85 to work with any considerable degree of efficiency it is absolutely necessary to equalize or approximately equalize the steam-pressure on the two ends of each reciprocating partition. To effect this, valves H are provided, 90 reciprocated by connecting-rods H', operatively connected to eccentrics H² on the shaft C', the valves sliding within steam-chests H', so that they alternately cover and uncover ports H³ and H⁴, formed in the casting A. 95 The ports H³ communicate with the spaces at the rear of the partitions D, the ports H⁴ being in communication with the exhaust. Each valve is inclosed in the usual steam-chest H⁵, to which steam is admitted by a 100 pipe H⁶. The eccentrics H upon the shaft C' are so arranged in relation to the eccentrics D⁷ on the same shaft that when the partitions D are advancing their respective valves H occupy such a position that steam is admitted to the rear of the partitions by the ports H³, such steam being exhausted by the ports H³ H⁴ during the return of the partitions.

To prevent leakage of steam between the 110 wall of the chamber and the outer circumference of the crank-disk C, the latter may be provided with a packing-ring of any well-known construction; also, for the same purpose the crank-pin C² may comprise a central 115 pin fixed to the disk C and surrounded by two approximately semicircular portions provided with packing between the two respective parts in any well-known manner.

What I claim as my invention, and desire 120 to secure by Letters Patent, is—

1. In a rotary engine, the combination of an annular cylinder, a central core around which the cylinder is formed, a shaft passed through the core concentric with the cylinder, 125 a piston within the cylinder, a member connecting the piston and shaft, oppositely-arranged partitions adapted to be reciprocated across the interior of the cylinder, and, in conjunction with the piston, to alternately 130 divide the interior of the cylinder into two steam-tight chambers, means for simultaneously reciprocating the partitions, means for admitting steam to the cylinder on one side

of the piston, means for exhausting on the opposite side of the same, means for regulating the pressure on the ends of the partitions, a valve to regulate the admission of steam to the cylinder and a valve to throttle or reverse the direction of the flow of steam to or from the cylinder, substantially as set forth.

2. In a rotary engine, the combination of an annular cylinder, a central core around which the cylinder is formed, a shaft passed through the core concentric with the cylinder, a piston within the cylinder, a member connecting the piston and shaft, oppositely-arranged partitions adapted to be reciprocated across the interior of the cylinder and, in conjunction with the piston, to alternately divide the interior of the cylinder into two steam-tight chambers, means for simultaneously reciprocating the partitions, means for admitting steam to the cylinder on one side of the piston, means for exhausting on the opposite side of the same, means for regulating the pressure on the ends of the partitions, and a valve to regulate the admission of steam to the cylinder, substantially as set forth.

3. In a rotary engine the combination of an annular cylinder open on one side, a central core around which the cylinder is formed, a shaft passed through the core transversely to the cylinder and concentric with the bore of the same, a disk mounted on the shaft and so situated as to close the open side of the cylinder, a piston carried by the disk, a partition reciprocated across the cylinder, a tenon on one side of the partition and a corresponding groove in the wall of the cylinder, means for reciprocating the partition, a recess in the core to receive the end of the partition when advanced across the cylinder, a balance-chamber within the core communicating with the cylinder and the recess which receives the end of the partition a recess in the upper and lower faces of the reciprocating partition, ports and passages formed in the wall of the cylinder and communicating with these recesses when the partition is advanced, and a valve to throttle or reverse the direction of the flow of steam through the passages in the wall of the cylinder, substantially as set forth.

4. In a rotary engine the combination of an annular cylinder open on one side, a central core around which the cylinder is formed, a shaft passed through the core transversely to the cylinder and concentric with the bore of the same, a disk mounted on the shaft and so situated as to close the open side of the cylinder, a piston carried by the disk, a partition reciprocated across the cylinder, a tenon on one side of the partition and a corresponding groove in the wall of the cylinder, means for reciprocating the partition, a recess in the core to receive the end of the partition when advanced across the cylinder, a balance-chamber within the core and communicating with the cylinder, and the recess which receives the end of the partition, a recess in the upper and lower faces of the reciprocating

partition, ports and passages formed in the wall of the cylinder and communicating with these recesses when the partition is advanced, 70 and a valve to regulate the admission of steam to the cylinder substantially as set forth.

5. In a rotary engine the combination of an annular cylinder open on one side, a central core around which the cylinder is formed, a shaft passed through the core transversely to the cylinder and concentric with the bore of the same, a disk mounted on the shaft and so situated as to close the open side of the cylinder, a piston carried by the disk, a partition reciprocated across the cylinder, a tenon on one side of the partition and a corresponding groove in the wall of the cylinder, means for reciprocating the partition a recess in the core to receive the end of the partition when advanced across the cylinder, a balance-chamber within the core and communicating with the cylinder and the recess which receives the end of the partition, and a valve to regulate the admission of steam to the cylinder 90 substantially as set forth.

6. In a rotary engine, the combination of a cylinder, a shaft arranged transversely of the cylinder and concentric with the bore of the same, a piston within the cylinder, a member connecting the piston and shaft, oppositely-arranged partitions adapted to be reciprocated across the interior of the cylinder, and, in conjunction with the piston to alternately divide the interior of the cylinder into two steam-tight chambers, means for simultaneously reciprocating the partitions, means for admitting steam to the cylinder on one side of the piston, means for exhausting on one side of the same, means for regulating the pressure on the ends of the partitions, a valve to control the admission of steam to the cylinder, and means for varying the position of the valve to vary the admission of the steam.

7. In a rotary engine, the combination of a cylinder divided into two chambers, a central core around which the cylinder is formed, a shaft extending transversely across the chambers, a crank-disk mounted upon the shaft intermediate the chambers, a crank-pin secured to each side of the crank-disk and fitting within the chambers and forming pistons, oppositely-arranged partitions for each chamber and adapted to be reciprocated across the interior of each chamber so as in conjunction with the pistons, to divide each of them into two steam-tight compartments, means for reciprocating the partitions, means for admitting steam to each of the chambers on one side of the pistons, means for exhausting on the opposite side of the same, means for regulating the pressure on the ends of the partitions, and valves to regulate the admission of steam to the chambers.

8. In a rotary engine, the combination of a cylinder divided into two chambers, and being provided with steam admission and exhaust passages E E', a central core around which the cylinder is formed, a shaft passed

through the core concentric with the cylinder, a crank-disk arranged intermediate the chambers, pistons carried by the disk, opposite partitions adapted to be reciprocated across the cylinder and each being recessed at opposite sides, the recesses being adapted to communicate with the steam and exhaust passages of the cylinder at a certain point in the movement of the partitions, means for simultaneously reciprocating the partitions as set forth, means for regulating the pressure on

opposite ends of the partitions, and valves to regulate the admission of steam to the steam-admission passages of the cylinder.

In testimony whereof I have signed my 15 name to this specification in the presence of two subscribing witnesses.

S. A. E. HICKSON.
